(57) **CLAIM**

The ornamental design for a pair of gloves, as shown and described.

DESCRIPTION

FIG. 1 is an elevational backhand view of a right hand glove according to the present invention;

FIG. 2 is an elevational palm-side view of the glove of FIG. 1 according to the present invention;

FIG. 3 is an elevational backhand view of a left hand glove according to the present invention;

FIG. 4 is an elevational palm-side view of the glove of FIG. 3 according to the present invention; and,

FIG. 5 is an elevational backhand view of the glove of FIGS. 1 and 2 and the glove of FIGS. 3 and 4, being worn by a user according to the present invention.

The right-hand glove of FIGS. 1-2 and the left-hand glove of FIGS. 3-4 are shown separately from one another for ease of illustration. The person shown in broken lines in FIG. 5 illustrates the claimed design in use. The broken-line subject matter forms no part of the claim.

1 Claim, 3 Drawing Sheets
